UNITED STATES PATENT OFFICE.

HENRY WELLINGTON, DECEASED, LATE OF NEW YORK, N. Y., BY LOUISE F. WELLINGTON, ADMINISTRATRIX, OF NEW YORK, N. Y.

PUMP.

1,125,611.

Specification of Letters Patent.

Patented Jan. 19, 1915.

Application filed January 17, 1914. Serial No. 812,715.

To all whom it may concern:

Be it known that I, LOUISE F. WELLINGTON, a citizen of the United States, and a resident of the city of New York, borough 5 of Manhattan, in the county and State of New York, administratrix of the estate of HENRY WELLINGTON, deceased, late a citizen of the United States and late a resident of the city of New York, borough of Manhattan, in the county and State of New York, who in his lifetime did invent a new and Improved Pump, do hereby declare the following to be a full, clear, and exact description.

15 The object of the invention is to provide a new and improved pump, more especially designed for use in wells, mines and other places from which water or other liquid is to be raised to a desired height, and arranged 20 to insure raising of the water or other liquid at a minimum expenditure of power, to prevent binding of the revolving lifting devices, to reduce destructive vibration to a minimum, and to permit convenient removal of the lifting devices for repairs or other purposes without disturbing the pump cylinders.

In order to produce the desired result use 30 is made of a pump cylinder provided with a sectional lining, each section having a deflector, a shaft extending centrally in the said cylinder and passing through the hubs of deflectors, and impellers secured to the shaft and alternating with the said deflectors.

For deep wells or mines use is made of 35 pump units, one above and out of vertical alinement with the other, the lower end of the cylinder of one pump unit being connected by an angular pipe joint with the upper end of the cylinder of the next lower unit, and the motor for the lower pump unit is mounted on a bracket adjustably mounted on the lower end of the cylinder of the 45 unit next above to permit of swinging the bracket to one side and with it the motor to permit removal of the lifting devices from the cylinder of this particular pump unit.

A practical embodiment of the invention 50 is represented in the accompanying drawings forming a part of this specification, in which similar characters of reference indicate corresponding parts in all the views.

Figure 1 is a side elevation of the pump 55 made of a series of units and as applied, and

with parts shown in section; Fig. 2 is a sectional plan view of the same on the line 2—2 of Fig. 1 and showing the motor for the lowermost pump unit swung to one side to permit removal of the lifting devices of this 60 pump unit; Fig. 3 is an enlarged sectional side elevation of the lower end of a pump unit, the section being on the line 3—3 of Fig. 4; Fig. 4 is a sectional plan view of the same on the line 4—4 of Fig. 3; Fig. 5 is a 65 sectional side elevation of the upper end of a pump unit and its connection with the next following unit; Fig. 6 is a side elevation of a pump formed of a single unit; and Fig. 7 is a side elevation of part of the cylinder 70 lining carrying the deflectors.

The pump illustrated in Fig. 1, consists of a series of pump units A, A', A² located one above the other and of such aggregate height to permit lifting water from a well 75 to a desired place of discharge. The pump illustrated in Fig. 6 is formed of a single pump unit A. Each of the pump units is provided with a cylinder B provided with an internal lining made in sections C, each provided at its lower end with tongues C' fitting into correspondingly-shaped cut-out 80 portions C² in the upper end of the next following section, so that the sections are rigidly connected with each other, as will 85 be readily understood by Fig. 7. The lowermost lining section C is provided with cut-out portions or seats C³ (see Fig. 3) engaging lugs D' formed interiorly on the foot D screwed or otherwise secured to the lower 90 end of the cylinder B. By the arrangement described the lining is supported in the cylinder B and is held against turning therein.

In each of the lining sections C is secured or integrally formed a deflector C⁴ provided 95 with wings C⁵ which extend throughout the height of the deflector, and each wing C⁵ is curved and has the upper and lower ends in vertical alinement, as plainly indicated in Fig. 3. The wings C⁵ extend radially from 100 a hub C⁶ in which is mounted to turn a sleeve E having a polygonal bore fitting onto a correspondingly shaped shaft F disposed centrally in the cylinder B. On the shaft F are secured impellers G alternating 105 with the deflectors C⁴, each impeller G being provided with two oppositely-disposed spiral blades G' extending from a hub G² having a polygonal bore in which fits the shaft F so that when the latter is rotated a 110

rotary motion is given to the corresponding impellers G while the deflectors C⁴ remain stationary.

By the arrangement described the liquid forced upward by an impeller G passes between adjacent wings C⁵ of the deflector C⁴ next above so that the swirling motion given to the liquid by the impeller is gradually changed into a quiet movement during its upward passage between the wings C⁵ of the deflector C⁴, and the liquid is taken up at the upper end of the deflector C⁴ by the spiral blades G' of the next following impeller G above. The upper and lower ends 10 of the sleeve E of each deflector C⁴ extend slightly beyond the corresponding upper and lower ends of the hub C⁶ thus forming bearings for the corresponding ends of the hubs G² of the impellers G to keep the adjacent ends of the blades G' and the wings C⁵ slightly spaced apart, as will be readily understood by reference to Fig. 3. By this arrangement any sediment that may be in the liquid is not liable to clog or lodge between adjacent impellers G and deflectors C⁴.

The lower end F' of the shaft F is made round and is journaled in a step D² forming part of the foot D, and the said lower end is provided with a collar F² resting on the step D² to support the shaft F (see Fig. 3). The upper end F³ of the shaft F is also made round (see Fig. 5) and extends through a stuffing box H held in a tubular offset I' of an angular joint or pipe connection I connecting the upper end of the cylinder B of one unit with the lower end of the cylinder B of the next following unit above, as plainly indicated in Figs. 1 and 5. The top of the upper end F³ of the pump shaft F terminates in a coupling member J mounted to turn on a ball bearing K held on the support L attached to the top of the offset I'. The coupling member J is engaged by a coupling member N held on the lower end of a shaft N' of a motor N² of any approved construction, preferably, however, of electrical type. The motor N² is mounted on a bracket O having a hub O' engaging the lower end of the cylinder B of the next pump unit above, and the said hub O' is preferably made in sections connected with each other by clamping bolts O² to permit of securely clamping the hub O' in position 50 on the cylinder B. When the bolts O² are loosened the bracket O can be swung around on the cylinder B (see Fig. 2) to disconnect the coupling member N from the coupling member J and to allow of lifting the shaft F and with it the impellers G and the lining C with the deflector C⁴ out of the corresponding cylinder B without disturbing the position of the latter. The angular offset I is provided on the top with a short 65 pipe I² to which is bolted or otherwise fas-

tened the lower end of the next following cylinder B above, as plainly indicated in Figs. 1 and 5. This joint I² carries a step I³ for the lower end of the shaft F of the next following unit to turn in, and the said joint I² is also provided with lugs I⁴ engaged by the seats C³ at the lower end of the lowermost pipe lining section C of the next following unit, as will be readily understood by reference to Fig. 5.

It will be noticed that by the arrangement described the cylinders B of succeeding pump units are out of vertical alinement and are connected with each other by the joint I to provide sufficient space for the bracket O and the motor N² employed for driving the corresponding shaft F. The offset I' of the joint I is provided with a lining I⁵ having an angular partition I⁶ through which extends the upper end F³ of the shaft F to prevent the liquid from passing into the offset I', as will be readily understood by reference to Fig. 5.

By the arrangement described any number of units may be readily joined together without taking up much lateral space and any desired number of pump units may be connected with each other to raise the liquid to the desired height.

It will further be noticed that in case the lining C is worn out it can be readily removed from the cylinder B and replaced by a new one, and in case the impellers G or the deflectors C⁴ become defective they can be removed from the cylinder to be replaced by new ones.

It is further understood that as no set screws, splines or similar fastening devices are used for fastening the impellers G to the shaft F, the center of gravity of the revolving lifting devices coincides with the center of the shaft F and an easy running of the pump is the result.

In practice the several motors N² are connected for simultaneous control from a single point.

In case the pump is formed of a single unit as shown in Fig. 6, then the offset I is provided with a goose neck outlet P for discharging the liquid to a suitable place of discharge, the vertical member of the goose neck P forming a bearing for the hub O' of the bracket O to allow of swinging the bracket and the motor N² into disconnected position the same as above described relative to the pump made of a number of units.

Having thus described my invention, I claim as new and desire to secure by Letters Patent:

1. A pump of the character described and formed of a series of pump units each having a cylinder, a shaft, impellers mounted on the said shaft, stationary deflectors in the said cylinders and arranged alternately with the said impellers, an angular joint 125

- connecting the lower end of the cylinder of one unit with the upper end of the cylinder of the next unit, a motor for rotating each shaft, and a bracket mounted to turn on the 5 lower end of the cylinder of one unit and carrying the motor of the unit next below.
2. A pump of the character described and formed of a series of pump units, each pump unit having a cylinder, a revolute shaft 10 held centrally in the said cylinder, alternately arranged impellers and deflectors in the said cylinder and of which the deflectors are stationary and the said propellers rotate with the shaft, a motor, a coupling for coupling the motor to the shaft outside of the cylinder, and a bracket mounted to swing 15 on the lower end of a cylinder of one unit and carrying the motor for the unit next below.
- 20 3. A pump of the character described, comprising a cylinder, a revolute shaft held centrally in the said cylinder and having a polygonal cross section, and alternately arranged impellers and deflectors in 25 the said cylinder, the deflectors being stationary and having a hub surrounding the shaft and the said impellers having hubs provided with polygonal bores fitting the 30 said shaft within the hubs of the deflectors to cause the impellers to rotate with the shaft.
4. A pump of the character described, comprising a cylinder, a lining for the cylinder made in sections, of which one is 35 provided at the end with tongues fitting into grooves in the next section, a deflector having wings forming part of a lining section, a revolute shaft held centrally in the said cylinder and having a polygonal cross section, 40 and impellers in the said cylinder and having hubs provided with polygonal bores fitting the said shaft, the said impellers being arranged alternately with the said deflectors.
- 45 5. A pump of the character described, comprising a cylinder, a lining for the cylinder made in sections, of which one is provided at the end with tongues fitting into 50 grooves in the next section, a deflector having wings forming part of a lining section, a revolute shaft held centrally in the said cylinder and having a polygonal cross section, 55 impellers in the said cylinder and having hubs provided with polygonal bores fitting the said shaft, the said impellers being arranged alternately with the said deflectors, and sleeves having polygonal bores fitting on the said shaft and rotating in the hubs of the said deflectors.
6. A pump of the character described, 60 comprising a cylinder, a lining for the cylinder made in sections, of which one is provided at the end with tongues fitting into grooves in the next section, a deflector having wings forming part of a lining section, 65 a revolute shaft held centrally in the said cylinder and having a polygonal cross section, impellers in the said cylinder and having hubs provided with polygonal bores fitting the said shaft, the said impellers being 70 arranged alternately with the said deflectors, and sleeves having polygonal bores fitting on the said shaft and rotating in the hubs of the said deflectors, each of the said deflectors having curved wings, the ends of 75 the wings being in vertical alinement, and each of the said impellers having oppositely-disposed spiral wings.
7. A pump comprising a cylinder, a lining fitting into the said cylinder and made 80 in sections, each lining section abutting at its end the next lining section and having an integral deflector provided with a hub and wings integrally connecting the hub with each lining section, a shaft extending centrally in the said cylinder and lining, and impellers secured on the said shaft and alternating with the said deflectors. 85
8. A pump comprising a cylinder a lining fitting into said cylinder and made in sections, each lining section abutting the next lining section and having integral deflectors provided with a hub, and wings integrally connecting the hub with the lining section, a shaft, impellers secured to the said shaft 90 and alternating with the said deflectors, each lining section having at its ends an extension to inclose the adjacent impellers. 95
9. A pump of the character described comprising a cylinder, lining for cylinder 100 made in sections, means for detachably connecting said sections to each other at their ends to prevent rotary movement of said lining, a deflector having wings and forming part of a lining section a shaft carrying said deflector, and impellers secured to the shaft and alternating with the said deflectors. 105
